(57) **CLAIM**

The ornamental design for an auto injection device with over mould grip, as shown and described.

DESCRIPTION

FIG. 1 is a perspective top view thereof;
FIG. 2 is a top view thereof;

FIG. 3 is a front view thereof;

FIG. 4 is a back view thereof;

FIG. 5 is a bottom view thereof;

FIG. 6 is a side view thereof; and,

FIG. 7 is an opposite side view thereof.

The broken line showing of parts of the drawings is included for the purpose of illustrating use and environment and forms no part of the claimed design.
